UNITED STATES PATENT OFFICE.

JAMES SAMUEL HEATH, OF MACEDON, NEW YORK, ASSIGNOR TO BICKFORD AND HUFFMAN COMPANY, OF MACEDON, NEW YORK, A CORPORATION OF NEW YORK.

ADJUSTABLE BEARING.

SPECIFICATION forming part of Letters Patent No. 717,192, dated December 30, 1902.

Application filed June 21, 1902. Serial No. 112,668. (No model.)

To all whom it may concern:

Be it known that I, JAMES SAMUEL HEATH, a British subject, and a resident of Macedon, in the county of Wayne and State of New York, have invented certain new and useful Improvements in Adjustable Bearings, of which the following is a specification.

My invention relates to adjustable bearings, and more particularly to that class of adjustable bearings designed to be employed in connection with the axle of a vehicle or of agricultural or other machines.

While my invention may be employed in connection with any shaft or axle for the purposes of illustration and to set forth a preferred mode of reduction to practice, I have shown and described it in the present case as applied to a seeding-machine or grain-drill, wherein it is especially necessary that an extended and accurate bearing be provided for the axle in its box because of the draft and pressure brought to bear thereon and the resulting tendency to cramp and cut into the axle unless the bearing be sufficiently extensive and accurately adjusted.

My invention consists in the construction and combination of parts now to be described and as finally pointed out in the claims.

Referring to the drawings, wherein the same parts are designated by the same letters of reference in all the figures, Figure 1 is an end view of the bearing and hanger therefor, the bed-piece of the frame and the axle being shown in section. Fig. 2 is a side view of the bearing and hanger, the frame being shown in section. Fig. 3 is a side view of the bearing, showing also in section a portion of the hanger.

The bearing or box proper, B, is shown in the form of an extended or elongated cylinder within which the axle A is inserted in the customary manner. The bearing B is provided on its upper surface with a projecting piece or extension B', the upper surface of which is formed as the convex section of a sphere having its center in the axial line of the box and axle therein, as shown in Figs. 2 and 3 and as indicated by dotted lines in Fig. 1. The hanger or bracket C is formed

with flanges D and E, which are bolted, respectively, to the bed-piece H and side piece I by means of the bolts G and F in the customary manner. The hanger C is further provided with the depending arms J J, which partially embrace the box B, the arms J J being formed internally with a spherical depression or concavity which engages and fits accurately upon the spherical convex extension B', formed upon the box B, as shown in Fig. 3, constituting in effect a species of universal joint. The box B is securely fastened within the arms J J of the hanger C by means of a curved or staple-shaped bolt K, which passes through the hanger C, down and around the box B, and again upward and through the hanger C, to which it is firmly attached by means of the nuts L L. Fillets or filling-in pieces B² B² may be inserted between the curved bolt K and the lower part of the box B in order to increase the rigidity of the bearing, if desired. An oil-cup M is formed upon the upper part of the spherical projection B' of the box B and projects through a recess O, formed in the hanger or bracket C, the recess O being formed of sufficient size to permit of an adequate amount of play therein for the oil-cup M, due to the varied adjustment of the box B in the hanger C. A spring N is pivoted to the hanger C at N' and is so shaped and inclined that when turned to operative position it covers and enters the mouth of the oil-cup M, so as to close it, and is afforded sufficient play to accommodate itself to the movement of the oil-cup M as the box B is adjusted. At the outer end of the box B a shield B³ is formed to exclude dirt and dust from the bearing.

It will be obvious, due to the engagement of the spherical projection B' on the box B with the spherical depression formed in the hanger C, that the proper adjustment of the box B with reference to the hanger C may be readily secured and that the parts may then be firmly fastened in adjusted position by tightening up the nuts L L upon the bolt K. In practice the axle A is ordinarily inserted within the box B when the machine or vehicle is set up, and thereby the proper position

is given to the box B with relation to the hanger C by reason of the spherical contact previously described, and the box may then be locked in adjusted position. Because of this construction and arrangement and because of the manner in which the axle by its insertion in the box turns the box to its proper position in the bracket or hanger the whole constitutes a species of self-aligning bearing.

10 While I have herein shown a preferred mode of reducing my invention to practice and as especially applied to a form of vehicle or agricultural machine, it will be obvious that it is applicable to any use where it 15 may be desired to secure this character of adjustment, and, moreover, that many changes and variations may be made therein without departing from the spirit of my invention.

Having thus described my invention, its 20 construction, and mode of operation, what I desire to secure by Letters Patent of the United States is as follows:

1. An adjustable bearing, comprising a box formed with a spherical projection, a bracket 25 or hanger provided with depending arms to partially embrace the box and having a spherical depression to fit the spherical projection upon the box, and a curved bolt passing through the hanger and around that part of

the box not embraced by the depending arms 30 so as to hold it in adjusted position.

2. An adjustable bearing, comprising a box formed with a spherical projection, a bracket or hanger provided with depending arms to partially embrace the box and having a spherical depression to fit the spherical projection upon the box, a curved bolt passing through the hanger and around the box to hold them in adjusted position, and fillets interposed 35 between the bolt and that part of the box not embraced by the depending arms.

3. An adjustable bearing, comprising a box formed with a spherical projection, a bracket or hanger provided with a spherical depression to fit the spherical projection on the box, 45 and means for securing the box and hanger in adjusted position, together with an oil-cup upon the box, and a spring pivoted to the hanger to bear upon the oil-cup, the hanger being formed with a recess to permit of the 50 necessary play of the oil-cup therein.

In testimony whereof I have subscribed my name to this specification in the presence of two subscribing witnesses.

JAMES SAMUEL HEATH.
